UNITED STATES PATENT OFFICE.

HARRISON H. DAVIS, OF THE PLAINS, OHIO.

SAFETY-SPOUT FOR POWDER-KEGS.

1,212,025.

Specification of Letters Patent.

Patented Jan. 9, 1917.

Application filed November 27, 1915. Serial No. 63,846.

To all whom it may concern:

Be it known that I, HARRISON H. DAVIS, a citizen of the United States, residing at The Plains, in the county of Athens and 5 State of Ohio, have invented a new and useful Safety-Spout for Powder-Kegs, of which the following is a specification.

The present invention relates to improvements in safety spouts for powder kegs, one 10 object of the invention, being the provision of a spout and means for attaching it to a powder keg, said spout being provided with an automatic closing valve whereby the same is normally closed to thereby seal the 15 keg for excluding the atmosphere and sparks.

A further object of the present invention, is the provision of a safety spout of the character indicated, the valve of which will 20 be opened when the spout is applied properly to a cartridge shell, the valve closing immediately as soon as the spout is removed from the shell.

A still further object of the invention is 25 the provision of a spout of the nature specified provided with a cutting, keg entering end and means for securing the spout to the head of the keg, such means being adjustable for kegs of various heights.

30 With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed without departing from the spirit of the invention.

40 In the drawing—Figure 1 is a perspective view of a keg with the present safety spout applied thereto. Fig. 2 is an enlarged vertical sectional view through the spout, a portion of the tie rod being broken away to foreshorten 45 the view. Fig. 3 is an enlarged sectional view of the outlet end of the spout applied to a cartridge shell. Fig. 4 is an enlarged bottom plan view of the entering end of the spout and the rim engaging jaw thereof. 50 Fig. 5 is an enlarged top plan view of the lower rim engaging jaw of the present device. Fig. 6 is a view similar to Fig. 3 illustrating a modification.

Referring to the drawing, the numeral 1 55 designates the spout which is provided with

the lower oblique cutting or entering end 2 adapted to be driven or projected through the top of the keg or can C. The spout 1 is provided with the powder directing bore or passage 3 and with one or more side outlets 4 adjacent the end 2.

An upper rim engaging jaw 5 is secured to the spout and to the upper end of a tie rod 6, whose lower end is exteriorly threaded, as at 7, and has slidable thereon, the lower rim engaging jaw 8, the jaw 5 being provided with the rim engaging groove 9, while the jaw 8 is provided with the rim engaging groove 10. The jaw 8 has a boss 8^a surrounding the rod 6. The groove 9 70 engages the upper rim of the can while the groove 10 engages the lower rim of the can so that a lock nut 11 having the operating handles 12 may be threaded onto the lower end of the rod 6 to clamp the jaws to the 75 rims of the can. By this means, the device is readily applied to cans of various sizes, and the rod 6 has a handle 6^a whereby the can may be readily carried and handled. The spout is preferably constructed of brass 80 or other nonsparking material. Below the jaw 5 and surrounding the cutting end 2 of the spout is a rubber or other gasket 13 which, when the spout penetrates a can, is adapted to seat upon the can around the 85 opening or aperture cut by the end 2, to prevent leakage.

The upper or outer end of the spout 1 is provided with the angularly or obliquely disposed nozzle 14 which is provided with 90 the internal inwardly-facing shoulder 15 at a point slightly ahead or beyond the junction of the bore 3 with the bore 3' of the nozzle, while slidable in the enlarged portion of the bore 3' behind the shoulder 15 95 is a cup-shaped valve 16 normally held in the seated position, as shown in Fig. 2, by means of the coiled expansion spring 17 entering the valve and held in place by means of the cap 18 threaded onto the rear 100 end of the nozzle 14.

When using the present device, the keg or can with the spout 1 applied thereto is inverted and the outlet end of the nozzle 14 is placed, as illustrated in Fig. 3, over an 105 upstanding pin 19 carried by the apertured powder directing cap 20 engaged upon the powder receiving shell 21 of the cartridge, and the pin will therefore raise and unseat the valve 16 against the tension of the spring 110

17, thus opening communication between the bores 3 and 3' so that powder may flow from the can out of the spout. As soon as the spout 1 is raised and the valve 16 is released from the pin 19, the spring 17 will cause the valve to seat against the annular shoulder 15 and thus cut off the flow of powder from the bore 3 to the bore 3'. Thus, an automatic closure device is provided for the spout.

In applying the present device to a keg or can, the nozzle 14 is grasped by the hand and the cutting end 2 is forced through the top of the can C adjacent the upper rim thereof, or so that the groove 9 may be engaged upon the rim when the cutting end 2 is "home" with the gasket 13 resting upon the top of the can and the apertures 4 below said top. The jaw 8 is now placed upon the lower threaded end of the rod 6 and the nut 11 is screwed thereon so as to move the jaw 8 and engage the groove 10 thereof with the lower rim of the can and thus simultaneously draw the jaw 5 closely upon the upper rim.

From the foregoing it will be seen that the device is easily applied to powder kegs and cans generally used, and a safety spout of simple character is provided.

30 In the modification illustrated in Fig. 6, the valve unseating pin or spindle 19' is integral with the valve 16', and an apertured tapered plug 20' is threaded upon the protruding end of the pin 19' which projects out of the outlet end of the nozzle 14. The plug 20' is readily inserted in the mouth of the cartridge shell 21, and when the nozzle is depressed, the nozzle will seat on the plug 20' and the valve 16' will be unseated 35 to allow the powder to flow into the shell 21. As soon as the spout is removed, the valve is seated under the influence of its spring. In this form, the valve unseating means is carried by the valve at all times, although 40 either of the devices illustrated in Figs. 3 and 6 can be used with the present spout.

Copies of this patent may be obtained for five cents each, by addressing the "Commissioner of Patents, Washington, D. C."

Having thus described the invention, what is claimed as new is:—

1. In a device of the character described, a spout having an entering end, a jaw attached to said spout and having a rim engaging groove, a tie rod having one end attached to said jaw, a second jaw slidable upon the other end of said rod and having a rim engaging groove, and a nut threaded upon the last mentioned end of the rod for moving the second jaw toward the first mentioned one for clamping a receptacle therebetween.

2. In a device of the character described, a spout having an entering end, a jaw carried by said spout and having a rim engaging groove, a second jaw having a rim engaging groove, a tie rod attached to one of said jaws and slidable through the other, and means carried by said rod to engage the jaw through which the rod is slidable for forcing said jaws toward one another to engage said grooves of the jaws with the end rims of a keg.

3. In a device of the character described, a spout having portions arranged at an angle with one another, one portion extending to opposite sides of the other, the first mentioned portion having a valve seat ahead of the second mentioned portion, a spring pressed valve slidable within the first mentioned portion to seat against said seat and to extend across the second mentioned portion when seated, a pin carried by the valve and projecting from the spout, and an apertured member carried by said pin to fit a cartridge shell or vessel and to abut against the end of the spout when the valve is unseated by said pin.

In testimony that I claim the foregoing as my own, I have hereto affixed my signature in the presence of two witnesses.

HARRISON H. DAVIS.
